UNITED STATES PATENT OFFICE.

THOMAS GRAHAM HAMILTON, OF GARY, INDIANA.

RAILWAY TIE.

Application filed July 29, 1922. Serial No. 578,418.

To all whom it may concern:

Be it known that I, THOMAS G. HAMILTON, a citizen of the United States, residing at Gary, in the county of Lake and State of Indiana, have invented certain new and useful Improvements in Railway Ties, of which the following is a specification.

My present invention relates to improvements in metallic railway ties and it has 10 special reference to that type of railway tie disclosed in my patent dated August 20, 1907, No. 863,987.

The tie disclosed in my patent aforesaid consists of a single piece of plate metal bent 15 or otherwise shaped into the finished tie without any connecting or supplementing holding elements except devices for holding the rails thereon.

My present invention has for its purpose 20 to provide a tie of substantially the same shape as that of my patented tie except that the tie body is formed of two like opposing longitudinal half sections having engaging flat ends adapted for overlapping in such 25 manner that they may be readily secured by riveting, and when secured extend along the length of the tie sufficiently to provide under bearing or base portions for the rail supporting ends of the tie only, whereby to 30 provide a tie whose top is open the full length thereof and whose bottom is likewise open along the length of the tie between the opposite closed bottom or base portions to thereby materially cheapen the cost of man- 35 ufacture of the type of tie shown in my patent aforesaid and make it possible to produce the tie by either rolling or pressing the two half sections into the desired form.

Another object of my present invention 40 is to provide an improved construction of tie embodying the same general characteristics present in my patented tie mentioned, composed of two like opposing longitudinal sections designed to provide increased fa- 45 cilities for tamping the tie base along the rail bearing ends thereof and for obtaining a greater ballasting effect along the full length of the tie than is possible to obtain when the base of the tie is in the nature of 50 a continuous solid bottom trough, as in my patented tie, before mentioned.

With the above general objects in view 55 my present invention is an all metal railway tie which embodies the peculiar features of construction and novel arrangement of

parts, all of which will be hereinafter fully explained, specifically pointed out in the appended claims and illustrated in the accompanying drawing, in which:

Figure 1 is a side elevation of one end ⁶⁰ of my improved railway tie with the rail secured thereon.

Figure 2 is a plan view of the tie portion shown in Figure 1.

Figure 3 is an end elevation of the tie ⁶⁵ with the rail thereon and looking in the direction of the arrow on Figure 1.

Figure 4 is a perspective view of the two half sections of the tie separated.

Figure 5 is a cross section of my improved ⁷⁰ tie taken on the line 5—5 of Figure 1.

In my present construction of metal railway tie, the body portion of the tie is composed of two longitudinally opposing like shaped half sections, the peculiar shape of ⁷⁵ which, after the said sections are bent to shape, is best shown in Figure 4, which shows that each section is a sheet metal blank bent upwardly and inwardly, as indicated by 3, and then outwardly the full ⁸⁰ length thereof as at 4, it being understood from the drawing, the flanges 4—4 of the opposing half sections project in opposite direction in planes parallel with the inwardly bent base portions 2 which, in my ⁸⁵ present construction, extend along each end only sufficient to provide base portions (in practice, extending from each end) from the rail bearing ends of the tie.

In my present form of tie, the side ⁹⁰ portions of each section do not extend the full height of the tie, the same being cut out the full length thereof between the rail bearing ends at which points the sides 3 extend down the full height of the tie and ⁹⁵ merge with the inturned flat base portions 2, the portions of the sides 3 between the rail bearing ends in my present tie structure form, as it were, shallow webs 30 that connect and constitute the stiffeners for the ¹⁰⁰ opposite ends or bearing portions of each tie section.

By reason of forming the tie body of two half sections as shown and described, the said half sections can be made by rolling, ¹⁰⁵ or pressed into the form shown, and by cutting out the base or trough portions, present in my patented tie mentioned, and also the greater portion of the sides 3 between the aforesaid rail bearing ends of ¹¹⁰

the tie, the weight of the material of which the tie is formed and the cost of making the tie is greatly reduced.

A further advantageous feature of my construction of tie, as shown and described is that by making the base portions 2 sufficiently wide to overlap, as shown in Figure 3, the said portions can be readily secured as solid base ends by riveting them 10 together as shown at 20-20.

When assembling the two opposing half sections of the tie the upper ends of the side portions 4 are sufficiently separated to provide ample space 5 for receiving the ballast which, in my present construction, fills through the open sides of the tie and also through the open bottom of the tie body, as is clearly shown in Figure 5.

To further provide for effectively ballasting the tie body, the base portions 2, at the rail bearing ends, are cut out to provide tamping openings 21, the said openings 21 being of sufficient length that their ends 21^a are exposed at each side of the rail to 25 facilitate tamping when the rails are applied.

In my present construction of tie, the rail bearing ends thereof are inwardly pressed, as indicated at 11, to provide inwardly extending stiffening braces of upwardly tapering form, and similar elements 12 are provided by pressing the merging portions of the upper ends of the sides 3 and the lateral flanges 4 the same as in my 35 patented tie before referred to.

From the foregoing description, taken in connection with the drawing, the complete construction of my present railway tie and its advantages will be apparent to those 40 familiar with the use and the manufacture of metallic railway ties of the general character described and shown.

What I claim is:

1. A metallic railway tie formed of two like opposing half sections each bent at the opposite ends thereof to provide flat base portions and sloping side portions, and with a web portion that extends lengthwise there-

of and merges at the ends with the side portions at the opposite ends, the top edge 50 of each section terminating in outwardly extending flanges that constitute the rests for the rails, the base portions of the two opposing sections being adapted for overlapping, and means for rigidly connecting the 55 said lapped base portions.

2. A metallic railway tie formed of two like opposing half sections each bent at the opposite ends thereof to provide flat base portions and sloping side portions, and with a web portion that extends lengthwise 60 thereof and merges at the ends with the side portions at the opposite ends, the top edge of each section terminating in outwardly extending flanges that constitute the 65 rests for the rails, the base portions of the two opposing sections being adapted for overlapping, means for rigidly connecting the said lapped base portions, the said attached base portions each having a slot- 70 way that extends lengthwise thereof and whose ends project beyond the transverse confines of the rail bases that seat across the top flanges of the said opposing sections.

3. A metallic railway tie formed of two longitudinal half sections bent along their opposite ends to form wide base portions and inwardly and upwardly sloping sides terminating at the upper end in outwardly 80 extending web flanges, the said base portions of the two sections being adapted for overlapping, means for securing the overlapping base portions to space the two sections apart to provide an intervening longitudinal space along the top face of the tie, each of the opposing sections including a longitudinal side web along the upper edge that merges with the top flanges and with the sloping side portions at the opposite 90 ends whereby to provide for the reception of ballast around the said webs and between the opposing sides at the opposite ends of the body.

THOMAS GRAHAM HAMILTON.
